Primary Examiner — David Muller(74) *Attorney, Agent, or Firm* — Kile Park Reed & Houtteman PLLC(57) **CLAIM**

We claim, the ornamental design for a medical syringe, as shown and described.

DESCRIPTION

FIG. 1 is a top and front perspective view of a medical syringe, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a cross-sectional view taken along the line '8-8' in FIG. 6.

The broken lines shown in FIG. 8 are included for the purpose of illustrating portions of the medical syringe that form no part of the claimed design.
